Primary Examiner — Llorellys Martinez*(74) Attorney, Agent, or Firm* — Dentons US LLP(57) **CLAIM**

The ornamental design for an earring, as shown and described.

DESCRIPTION

FIG. 1 is a front side view of an earring showing my new design;

FIG. 2 is a back side view thereof;

FIG. 3 is a top side view thereof;

FIG. 4 is a bottom side view thereof;

FIG. 5 is a right side view thereof;

FIG. 6 is a left side view thereof;

FIG. 7 is a front perspective view thereof;

FIG. 8 is another front side view thereof;

FIG. 9 is another back side view thereof;

FIG. 10 is another top side view thereof;

FIG. 11 is another bottom side view thereof;

FIG. 12 is another right side view thereof;

FIG. 13 is another left side view thereof; and,

FIG. 14 is another front perspective view thereof.

The broken lines shown in the drawings illustrate environmental subject matter only that forms no part of the claimed design.

1 Claim, 14 Drawing Sheets(56)
